(57) **CLAIM**

The ornamental design for a cap with a size adjusting fastener, as shown and described.

DESCRIPTION

FIG. 1 is a perspective view of a cap with a size adjusting fastener showing my design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top plan view of the cap with a size adjusting fastener secured together and removed from the cap of FIG. 1;

FIG. 9 is a bottom plan view thereof;

FIG. 10 is a top plan view of the cap with a size adjusting fastener separated and removed from the cap of FIG. 1; and, FIG. 11 is a bottom plan view thereof.

The broken lines depict portions of the cap with a size adjusting fastener that form no part of the claimed design.
